FIG. 1 is a perspective view of a dried noodle showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged sectional view of the left end of FIG. 1;

FIG. 9 is an enlarged view of FIG. 4; and

FIG. 10 is an enlarged view of FIG. 5;

FIG. 11 is a perspective view of a second embodiment of a dried noodle showing our new design;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof;

FIG. 18 is an enlarged sectional view of the left end of FIG. 1;

FIG. 19 is an enlarged view of FIG. 14; and,

FIG. 20 is an enlarged view of FIG. 15.
